UNITED STATES PATENT OFFICE.

DAVID A. SEALEY, OF EAST ORANGE, NEW JERSEY.

PHONOGRAPHIC SOUND BOX.

1,416,582.

Specification of Letters Patent. Patented May 16, 1922.

Application filed January 21, 1920. Serial No. 352,959.

To all whom it may concern:

Be it known that I, DAVID A. SEALEY, a citizen of the United States, residing at East Orange, in the county of Essex and State of New Jersey, have invented certain new and useful Improvements in Phonographic Sound Boxes, of which the following is a specification, reference being had to the accompanying drawings.

10 This invention relates to sound boxes for phonographs or other sound recording or reproducing machines, and the general object of the invention is to provide a sound box so constructed that sound vibrations will be considerably amplified or rendered stronger, either when the sound box is used as a recording sound box or as a reproducing sound box.

A further object in this connection is to 20 provide a sound box which, by a suitable manipulation, can be caused to increase or decrease the sound reproduced.

A further object is to provide a sound box having a pair of diaphragms, one of the diaphragms being connected to the recording or reproducing stylus carrying arm, as the case may be, and the other diaphragm being entirely free, the space between said diaphragms being filled or partly filled with liquid, and provide means whereby the space between the diaphragms may be filled more or less full of liquid to thus modify the sound vibrations which are transmitted through the diaphragms and thus modify 35 the sound reproduction or the recorded sound.

A further object is to provide a sound box of the character described with an air chamber providing for the outlet of air as the sound box is being filled with liquid and providing, in effect, an air cushion against which the liquid in the sound box bears at all times.

A further object is to provide a connection to the sound box as described, a filling chamber adapted to be filled with liquid and having means whereby the liquid in said chamber may be forced into the sound box to more or less fill the space between the diaphragms as may be desired.

Other objects will appear hereafter.

My invention is illustrated in the accompanying drawings, wherein:—

Figure 1 is a front elevation of a sound box constructed in accordance with my in-

vention, the box being partly broken away and the filling chamber being in section;

Figure 2 is an enlarged sectional view on the line 2—2 of Figure 1;

Figure 3 is a like view to Figure 1 but 60 showing a modified form of the filling device;

Figure 4 is an enlarged sectional view of the chamber 19 to show the outlet valve thereof.

The preferred form of my sound box is illustrated in Figure 1, and this form of the sound box comprises an annular rim or body 10, which is angular in cross section, as illustrated particularly in Figure 2. Disposed against the base flange of this rim is a gasket 11, and against this gasket is disposed a diaphragm 12. This diaphragm may be made of metal, mica, glass, ebonite or any other suitable material such as is 75 commonly used in sound boxes today. Disposed upon this diaphragm 12 is the annular and relatively thick gasket 13, and disposed against this gasket is the diaphragm 14, which also may be made of any desired 80 material. Against this diaphragm is disposed a gasket 15, and bearing against this gasket is an annular plate 16 having a relatively thickened rim 17 which bears against the gasket 15 and against the rim of the 85 body 10 and is held thereto in any suitable manner, as by screws 18. The plate 16 is formed with the relatively thickened rim in order to space the body of the plate from the diaphragm 14 and to provide a resonating chamber around the margin of the diaphragm 14. It will be understood that the two sections of the sound box body, the gaskets, and the diaphragms are to be held in close contiguity with each other so that the 95 diaphragms will be securely clamped at their margins and will have liquid-tight engagement with the gaskets.

As illustrated in Figure 1, the upper portion of the wall of the sound box is provided with a globular chamber 19 communicating by a duct 20 with the interior of the space between the diaphragms 12 and 14. This duct 20 at its inner end is preferably flaring, and the wall of chamber 19 is provided with a relatively small bleed and preferably valved opening or vent 21.

While I may simply provide means for filling the space between the diaphragms more or less full with liquid, I preferably 110

- 2
- provide, as shown in Figure 1, a filling chamber 22 which, as illustrated in Figure 1, is in the form of a cylinder, this filling chamber at its lower end being connected by 5 a duct 23 with the interior of the sound box and being provided with a piston 24 operated by means of a screw-threaded stem 25 having a head at its outer end. This stem may be screw-threaded into the end of the 10 cylinder, or the stem might have screw-threaded engagement with the piston. In any event, the stem is so mounted that a rotation of the stem in one direction will cause the piston to move into the cylinder, forcing the contents of the cylinder out into the 15 space between the diaphragms 12 and 14, and a reverse movement of the piston will cause the liquid between the diaphragms to pass back into the cylinder 22.
- 20 I do not wish to be limited to means for shifting this piston longitudinally. I may, for instance, in place of the adjustable piston, as shown in Figure 3, use a flexible rubber tube 26 operatively connected to the space 25 between the diaphragms, this tube being provided at its extremity with a bulb 27 whereby a compression of the bulb or ball 27 would cause liquid to be forced into the sound box, whereas an expansion of the bulb 30 would withdraw liquid from the sound box. Assuming that the sound box is provided with the cylinder 22 and the adjustable piston 24, it is obvious that if it is desired to fill the space between the diaphragms 12 35 and 14 with liquid, the piston 24 is forced down in the cylinder 22 to its fullest extent and this will force all the liquid in the cylinder 22 into the space between the diaphragms and fill this space.
- 40 Inasmuch as the duct 20 is located at the uppermost portion of the sound box, it follows that any air within the sound box will not be forced out through this duct and will not be trapped within the sound box, and preferably I so proportion the capacity of the sound box, that is the space between the two diaphragms and the cylinder 22, that upon a full depression of the piston the liquid will be forced up into the chamber 19 so as to 45 prevent any inlet of air, and further form a static head, as it may be termed, which will compensate and permit the vibrations of the mass of liquid.
- 50 It will be obvious that if the space between the diaphragms was closed and liquid was forced into the space under pressure, that the liquid being incompressible, there would be but little elasticity in the sound box but that the diaphragms would be forced outward away from each other with considerable 55 force. By providing this globular chamber 19, however, with its very small vent, I provide for a certain amount of elasticity in the liquid even though the space between the 60 diaphragms is filled and the vent opening is so small, being a mere pinhole, that while the air can escape, there is a certain amount of resistance to the passage of air so that the air in the upper portion of this chamber 19 acts elastically and exerts an elastic pressure 70 upon the liquid when the diaphragms are vibrating and the liquid is vibrating.
- 65 Of course, if it be desired, as shown, to make the chamber 22 of less capacity than the sound box, a filling opening may be provided, closed by a screw plug 28. Thus, the space between the diaphragms may be normally partly filled with liquid and then a depression of the piston 24 will cause sufficient liquid to be forced into the space between the diaphragms to entirely fill this 80 space. It is obvious, however, that in the simplest form of my invention the cylinder 22 can be omitted and the adjustment of the liquid within the space between the diaphragms be secured simply by filling this space more or less full through the opening normally closed by the plug 28 or emptying the liquid out to any desired amount through the opening and closing the opening again. 90 By providing the cylinder 22, however, with the adjustable piston thereon, I provide for a relatively delicate regulation of the sound box and of the sounds reproduced thereby, and it is obvious that where a bulb is used, as illustrated in Figure 3, the amount of liquid within the sound box can be constantly 95 changed and thus the loudness or softness of the tone be constantly modified as may suit the operator.
- 100 In actual practice I fill, or partly fill, the space between the diaphragms with water, though it is obvious that other liquids such as glycerine or oil might be used and attain good results. I do not wish to be limited to a liquid, however, as I have found that a semi-liquid, as for instance, a jelly-like substance might be used between the two diaphragms, this jelly-like substance constituting a body which is adapted to transmit elastic vibrations. I have found in actual practice, however, that the action of a liquid or semi-liquid disposed between the diaphragms is entirely different from the action 110 of a gas, such as air, between the diaphragms. A sound box having two diaphragms and with normal air pressure between the diaphragms will reproduce sounds but not very distinctly. As the air pressure between these diaphragms is increased, no difference can 115 be detected in the tone until the air pressure is considerable and sufficient to cause the diaphragms to bulge. At this point, the tone produced appears to be very slightly deadened or muffled, though this deadening 120 of the tone is fairly perceptible, and this deadening tone would seem to be caused by the highly compressed air, which actually prevents the diaphragms from vibrating and this interferes with the quality of the music. 125
- 130

Where liquid is used between the diaphragms, however, in place of air, a very great difference is noted. The moment a small quantity of liquid, such as water, is placed between the diaphragms, the tone is immediately sharpened and made more clear and distinct and loud. As the amount of liquid is increased, the tone is gradually softened until, when the sound box is entirely filled with liquid, the tone is the softest. I have found that mercury produces a fairly good tone and that the loudness and softness of the tone may be controlled, but on account of its excessive weight, mercury is not as practical as a liquid, such as water. A liquid or semi-liquid such as described may be forced to partly or entirely fill the space between the diaphragms or may be compressed to a greater or less extent by obvious means, such as the piston 24 shown in Figure 1, or an equivalent device.

I have found that a sound box constructed in accordance with my invention has many advantages over the ordinary sound box. It transmits or translates vibrations into sound or sound into vibrations much better than an ordinary sound box. When it is desired that the sound delivered by the sound box shall be particularly loud, then the space between the diaphragms is emptied of liquid or other material. When, however, it is desired that the sound shall be softened, the space between the diaphragms is more or less filled with liquid, depending upon the loudness of the sound desired, and this softens the sound without, however, causing any loss in the delicacy of the sounds or muffling the tones. Thus, by the provision of the cylinder and piston described or equivalent devices, the sound box may be adjusted to suit any particular record or any particular condition of reproducing or recording. Of course, the sound box is to be provided with the usual stylus carrying arm *a* and stylus *b*, and it is obvious that the sound box may be used either with a laterally cut record or with a "hill and dale" record, or for recording laterally cut or "hill and dale" records. In practice I find that it is best to space the diaphragms relatively close to each other but sufficiently far from each other so that no capillary action will take place, as if the diaphragms are too near to each other, the liquid will not fill the space uniformly.

Preferably, though not necessarily, I prevent the passage of liquid through the vent 21 and thus prevent the passage of liquid out of the space between the diaphragms by means of a valve 29 constituting, in effect, a float valve. This valve may be of any suitable design but, as shown, has a valve stem 30 which extends up through the vent opening but is relatively smaller than the vent opening and is supported in any

suitable spider 33 mounted upon the chamber 19. This valve is preferably a float valve so that when the liquid rises in chamber 19 above a certain height, this valve will close and prevent the escape of liquid. The function of this valve is to permit pressure to be applied to the liquid between the diaphragms 12 and 14, as I find in actual practice that modulations of sound may be secured, not only by filling the sound box more or less full or liquid but by filling the sound box entirely full of liquid and then vary the pressure on this liquid by means of the piston 24 or by means of the bulb 27. I find, for instance, that the pitch of the reproduced sound may be gradually increased by allowing the water or other liquid between the diaphragms to be gradually withdrawn and that when the sound box is entirely full, if then the outward movement of liquid be prevented, as by the valve 29, and pressure be applied upon the liquid between the diaphragms, the loudness of the sound will be varied, the pressure applied upon the liquid tending to stiffen the diaphragms. Of course, I do not wish to be limited to the use of the valve 29 or to the position of this valve within the chamber 19, or to the use of this chamber 19 under all circumstances.

While I have illustrated certain forms of my device which I have found to be thoroughly effective in practice, yet I do not wish to be limited thereto, as it is obvious that many modifications might be made in the details of construction and arrangement of parts without departing from the spirit of my invention.

I claim:—

1. A phonographic sound box having a body, two diaphragms spaced from and disconnected from each other, the space between said diaphragms containing a liquid adapted to transmit the vibrations of one diaphragm to the other, and manually adjustable means permanently connected to the sound box for exerting more or less pressure on said material.

2. A phonographic sound box including a body, two parallel diaphragms spaced from each other and disposed a relatively short distance apart, the space between said diaphragms containing liquid, and manually operable means mounted upon the sound box and communicating with the space between the diaphragms for withdrawing liquid from between the diaphragms or forcing liquid thereinto.

3. A phonographic sound box including a body, two parallel diaphragms mounted upon the body and spaced from each other a relatively short distance, the space between said diaphragms containing liquid, a chamber mounted upon the body and having a vent opening and communicating opposite the vent opening with the space between the

- diaphragms, the sound box having means whereby liquid may be forced into the space between the diaphragms to fill said space and partly fill the said chamber.
5. A phonographic sound box having a body, two spaced diaphragms disconnected from each other, the peripheral wall of said space being provided with a duct leading therefrom, and a chamber into which said 10 duct opens, the space between said diaphragms being filled with liquid, and manually operable means connected to the sound box and communicating with said space whereby more or less liquid may be forced 15 into said space or withdrawn therefrom.
5. A phonographic sound box having a body, two spaced diaphragms disconnected from each other, the peripheral wall of said space being provided with a duct leading 20 therefrom, and a chamber into which said duct opens, the space between said diaphragms being filled with liquid, and means connected to the sound box and communicating with said space whereby more or less 25 liquid may be forced into said space or withdrawn therefrom, said means comprising a cylinder, and a piston adjustable in the cylinder.
6. A phonographic sound box comprising 30 an annular body, spaced parallel diaphragms disposed within said body, gaskets holding said diaphragms in spaced relation and supporting the margins of the diaphragms against the body, means for clamping 35 the diaphragms within the body, the peripheral wall of the box being provided with an outlet duct and an inlet duct, a chamber connected to the outlet duct and having a very small vent opening, the outlet 40 duct being disposed at the uppermost portion of the sound box, a cylinder connected to the inlet duct, a piston movable in said cylinder, and means for adjusting the piston at any desired position, said piston 45 ton and the space between the diaphragms being adapted to be filled with liquid.
7. A phonographic sound box comprising
- a body, spaced diaphragms carried upon the body and disconnected from each other, the peripheral wall of the sound box between 50 said diaphragms being provided with an outlet duct disposed at the uppermost portion of the sound box, a chamber connected to the outlet duct and having a relatively small vent opening, and means mounted upon the sound box whereby liquid may be forced 55 into the space between the diaphragms and into the chamber or withdrawn therefrom.
8. A phonographic sound box comprising 60 a body, spaced diaphragms carried upon the body and disconnected from each other, the peripheral wall of the sound box between said diaphragms being provided with an outlet duct disposed at the uppermost portion of the sound box, a chamber connected to the outlet duct and having a relatively small vent opening, means mounted upon the sound box whereby liquid may be forced 65 into the space between the diaphragms and 70 into the chamber or withdrawn therefrom, and a float valve controlling the vent opening in the chamber and preventing the escape of liquid when the chamber is filled 75 but permitting the inlet of air upon a reduction in the volume of liquid within the chamber.
9. A phonographic sound box comprising a body, spaced diaphragms disconnected from each other, means for forcing liquid 80 into the space between the diaphragms or withdrawing it therefrom, and valves controlled means permitting the passage of air out of the space between the diaphragms when the amount of liquid between the diaphragms is increased but preventing the escape of liquid when the space between the diaphragms is filled with liquid and under pressure, said valve controlled means permitting the inlet of air when the amount of 85 liquid between the diaphragms is decreased.
- In testimony whereof I hereunto affix my signature.

DAVID A. SEALEY.
